UNITED STATES PATENT OFFICE

161,076

VACUUM CLEANER NOZZLE OR SIMILAR ARTICLE

Oliver L. Allen, Riverside, Conn., assignor to
Electrolux Corporation, Old Greenwich, Conn.,
a corporation of Delaware

Application December 13, 1947, Serial No. 143,137

Term of patent 14 years

(Cl. D9—2)

To all whom it may concern:

Be it known, that I, Oliver L. Allen, a citizen of the United States of America, residing in Riverside, Connecticut, have invented a new, original, and ornamental Design for a Vacuum Cleaner Nozzle or Similar Article, of which the following is a specification, reference being had to the accompanying drawing, forming part thereof:

Fig. 1 is a bottom front perspective view of a vacuum cleaner nozzle or similar article showing my new design;

Fig. 2 is a bottom rear perspective view of the nozzle of Fig. 1;

Fig. 3 is a top front perspective view of the nozzle shown in the preceding figures; and

Fig. 4 is a top rear perspective view of the nozzle.

I claim:

The ornamental design for a vacuum cleaner nozzle or similar article, as shown.

OLIVER L. ALLEN.
